INVENTOR:
J. B. Mallory
By
Atkins & Atkins,
ATTORNEYS.

UNITED STATES PATENT OFFICE.

FREDERICK B. MALLORY, OF PORTLAND, OREGON.

PULLEY BLOCK.

Application filed April 10, 1923. Serial No. 631,196.

To all whom it may concern:

Be it known that I, FREDERICK B. MALLORY, a citizen of the United States of America, and resident of Portland, in the county of Multnomah, in the State of Oregon, have invented certain new and useful Improvements in Pulley Blocks, of which the following is a specification, reference being had to the accompanying drawings.

My invention belongs to a class of pulley blocks which are adapted for service in inaccessible situations and for comparatively long periods, during which each block must be dependable for endurance and performance of duty without attention, and must be constantly self-lubricating the while, in any of the numberless operative positions which it may and does from time to time assume in use.

The main object of my invention is to produce a block which may be relied upon to satisfy all the aforesaid requirements of the class of blocks designated.

What constitutes my invention will be hereinafter specified in detail and succinctly set forth in the appended claims.

In the accompanying drawings,

Figure I is an edgewise elevation, partly in medial vertical section of a block exhibiting my invention in present preferred form of embodiment.

Figure II is a transverse section on the line II—II of Figure I.

Figure III is a section of a portion of Figure I, taken on the line III—III thereof, and looking downwardly, the sheave and its hub being omitted.

Figure IV is a detail sectional view taken on the line IV—IV of Figure III.

Figure V is a perspective of one of the journal-bearings of my block detached and looking towards the inner end thereof.

Figure VI is a transverse section on the line VI—VI of Figure III, looking upwardly.

Referring to the numerals on the drawings, 1 and 2 indicate, respectively, two block-sides which are counterparts one of the other, and which, when bolted together in operative assemblage as with a shackle 3 and a cross-head 4, are designed and adapted to carry between them a sheave 5, which is fixed to a rotative shaft 6 pro-

vided with suitable journals 7 for mounting it in the block.

The above enumerated elements, so far as above described, may be of any usual or preferred construction.

My invention comprehends means provided for improving the construction of each block-side with a view to increasing its structural strength, and to embodying into such construction definite provision of new and useful means for self-lubrication of the wearing parts of the block.

To those ends, I provide a lateral assembling member 8 preferably consisting of an external shell of such smooth curvilinear contour in cross section as is illustrated, the same being deemed most suitable to contribute resistance to crushing force from without, and relief, in large measure, from shock as the result of direct impact with objects against which there is, in use, constant danger of collision.

Upon the member 8, say within the hollow of the shell which is the preferred form of the assembling member 8, I provide a plurality of integral webs which afford, individually and collectively, a support, of truss effect, for the member 8 and for one another. The number of said webs comprehends, for example, a marginal rim 9; a pair of walls 10 extending from one side of said rim to terminals disposed on opposite sides of the center of the rim and spaced apart within the shell to best advantage for strengthening the same; a pair of divergent walls 11 which proceed from the ends of the walls 10 into which they merge; a segmental wall 12 with its supporters 13, concentric to the rim 9 and uniting the opposite flaring ends of the walls 11; and a journal-bearing support 16 adapted to carry a bearing 17,

which in the present instance is formed independently of the block-side and will be hereinafter fully described. The webs above enumerated are, in effect, a truss, being united and preferably cast in an integral whole with the member 8 and conjoint cover-plates 14 and 15, which serve, respectively, to support transversely the enclosure defined by the wall 10 and the rim 9 on the one part, and that defined by the walls 11 and 12 on the other.

The width of the space which separates the walls 10, and the angle of divergence

between the walls 11, as well as the longitudinal extent of the latter as limited by the disposition of the wall 12, should be such as to qualify said walls or webs collectively to the lending to the shell a maximum degree of resistance against outside crushing force, and also the lending of strength, stiffness, and rigidity to the journal-bearing support 16 which is disposed in the space between the walls 8 and 15 as shown in Figures I and VI.

The relationship between the walls 10 and the walls 11, respectively, is also, in part, determined by the fact that they constitute the side walls of the two separate lubricating chambers which constitute independent sources of lubricant supply to the respective journals 7.

The walls 10 are preferably parallel to each other and are preferably separated by a distance greater than the diameter of the journal 7, plus the two thicknesses of the journal-bearing 17, said parts 7 and 17, being an assemblage of members which collectively constitute a partition operatively dividing the two lubricant chambers from each other. The walls 10 terminate, respectively, in oppositely inturned lips 19, which are preferably formed integrally with contiguous walls 10 and 11 where they unite. By providing a width substantially as above specified between the walls 10, provision is made for imparting to the upper surfaces 20 of said lips, respectively, a gentle curvature whereby each of said surfaces is, for the promotion of the flow of lubricant, made flush with the inclined faces 21, respectively, of partition bars 22 wherewith the journal-bearing 17 is provided, in the manner and for the purpose which will presently be more fully set forth.

Below the lip 19 (the block being regarded as normally suspended from the shackle 3) the walls 11 set out divergently therefrom, the angle of their divergence being substantially that at which, whenever the walls 10 assume a horizontal or downwardly inclined position, as they are constantly liable at any time to do in service, the lubricating chamber which is bounded on opposite sides by the wall 11 will begin to feed by gravity a suitable lubricant to the juxtaposed surfaces of the journal 7 and its bearing 17. In other words, so long, on the one hand, as the walls 10 occupy any position above the horizontal between the vertical and the horizontal, the lubricant chamber of which they constitute the side walls will, by action of gravity, contribute a supply of lubricant to the bearing surfaces with which they communicate. On the other hand, at the moment substantially when the lubricant supply of one lubricant chamber ceases to flow by gravity, because of change of position of the block, then the other lubricant

chamber beings to functionate to keep said bearing surfaces properly lubricated.

It should be observed that the reciprocal functioning of the two lubricating chambers in the manner just described takes place without regard to the plane in which the sheave 5 happens to be rotating, and that the pair of lubricating chambers in one block-side, in disposition and functioning capacity, corresponds to the like pair of chambers in the companion block-side.

The journal-bearing 17 which preferably is formed separate from the block-side, is of a generally cylindrical shape, as shown for example in Figure V. It is preferably made of one piece of brass and of a weight sufficient to qualify it as a structural member of the block-side as well as a bearing member. It is preferably provided near its end nearer the sheave 5 with an internal annular recess 23 for the reception of a suitable packing ring 24.

The member 17 is confined within the journal-bearing support 16 of each block-side by undercut 25 in the lower sides of the lips 19 as well as by an annular seat 26 in the shell 8 and by the reenforced wall 27 which defines an encircling aperture in the conjoint cover-plates 14 and 15. It is anchored therein against rotation, as by lateral lugs 28 introduced from the inside of the block-side into close fitting recesses provided for them, respectively, in the opposite lips 19.

The upper half of the member 17 is provided, in effect, with a single aperture 29 extending between the inside of the shell 8 and the opposing face of the cover-plate 14, and from one lip 19 to the other. This is true despite the fact that a middle cross-bar 30, as shown in the drawings, may, without material obstruction to flow of lubricant, be employed, if desired, to lend stiffness to the cylindrical member 17.

In the side of the member 17 opposite the aperture 29 therein, I provide adjacent to the walls 11, respectively, two lubricant feed slots 31 whose lateral walls 32, are located preferably in a plane approximately parallel to the inner surfaces of the walls 11, respectively, and at opposite lateral extremities of the support 16, as shown in Figure III.

34 indicates a washer confined about one of the journals 7 between the adjacent end of the member 17 and the hub 35 of the sheave 5. The function of the two washers 34 is to take the entire end-thrust in one direction or the other of the shaft 6, to which said sheave is united.

Each lubricant chamber is provided with a filling nipple 36 and a stopper, preferably a screw plug 37 threaded therein and preferably countersunk in the shell or member 8.

The following brief description will, in view of the foregoing specification, suffice

to make the operation of my block clearly intelligible.

A lubricant preferably in the form of grease is supplied to the interiors of the several lubricant chambers through their respective nipples 36 which are afterwards securely closed as by their respective plugs 37. The block is then ready for use with assurance that it will be adequately lubricated in any of the numberless positions it may and is likely to assume in use.

The end-thrust of the shaft 6 in either direction is caught upon one of the two washers 34 and by it communicated to the journal-bearing 17 to whose end it is contiguous. In this regard the said member 17 becomes more than a mere bushing, and carries the major part of the working strain of the block. In order to capacitate it for performance of that function, it is not only made of adequate weight of metal to endure the strain, but is incorporated into the block-side at a point where the structure thereof is, as above specified, braced on all sides by webs distributed with truss effect to receive and withstand the strain.

What I claim is:

1. In a device of the class described, a side-bearing member having an opening for a shaft and including a plurality of independent lubricant reservoirs closed from communication with one another and disposed on substantially opposite sides of the shaft opening respectively, and said member having means whereby said reservoirs may communicate with a shaft extending through said opening, respectively, at substantially opposite sides thereof.

2. A side bearing member having an opening for a shaft and including a plurality of independent lubricant reservoirs closed from communication with one another and disposed on substantially opposite sides of the shaft opening, said reservoirs being adapted together to substantially encircle a shaft extending through said opening and said member having means whereby said reservoirs may communicate with the shaft, respectively, at substantially opposite sides thereof.

3. A side-bearing member having an opening therein for a shaft and including a plurality of independent lubricant reservoirs closed from one another and disposed, respectively, substantially above and below said opening, said member having means whereby said reservoirs may communicate respectively with substantially opposite sides of a shaft extending through the opening.

4. A side-bearing member having an opening therein for a shaft and including a plurality of independent lubricant reservoirs closed from one another and disposed respectively substantially above and below said opening, said member having means whereby

said reservoirs may communicate, respectively, with substantially opposite sides of a shaft extending through the opening and said reservoirs being adapted together to substantially encircle said shaft.

5. In a device of the class described, a side plate having a shaft bearing, and independent, separate lubricant reservoirs positioned respectively above and below the axis of said bearing, one adapted to deliver lubricant to the upper and the other to the lower portion of the bearing, said side plate having openings therein leading from said reservoirs to the bearing.

6. In a device of the class described, a block-side having a shaft bearing and lubricant reservoirs on opposite sides of the bearing, one of said reservoirs having side walls substantially parallel to each other, and the other reservoir having side walls diverging from each other and from the longitudinal axis of the first named reservoir.

7. In a device of the class described, a block-side having a shaft bearing and lubricant reservoirs on opposite sides of the bearing, one of said reservoirs having side walls substantially parallel to each other, and the other reservoir having side walls diverging from each other and from the longitudinal axis of the first named reservoir, said second reservoir having a bottom wall connecting the side walls, and block-side reinforcing ribs extending outwardly from said bottom wall in planes substantially radial with respect to said bearing.

8. In a device of the class described, a block-side having a shaft bearing and lubricant reservoirs on opposite sides of the bearing surfaces, one of said reservoirs having side walls substantially parallel to each other, and the other reservoir having side walls diverging from each other and from the longitudinal axis of the first named reservoir, said second reservoir having a bottom wall connecting the side walls, and block-side reinforcing ribs extending outwardly from said bottom wall in a plane substantially radial with respect to said bearing, said bearing having openings at the diverging side walls of the second reservoir communicating with the said reservoir.

9. In a device of the class described, a block-side having a shaft bearing and lubricant reservoirs on opposite sides of the bearing surfaces, one of said reservoirs having side walls substantially parallel to each other, and the other reservoir having side walls diverging from each other and from the longitudinal axis of the first named reservoir, said second reservoir having a bottom wall of segmental form connecting the side walls, and block-side reinforcing ribs extending outwardly from said bottom wall in planes substantially radial with respect to said bearing.

10. In a device of the class described, a block-side having a shaft bearing, a plurality of separated, independent lubricant reservoirs disposed on opposite sides of the bearing, one of the said reservoirs having side walls provided with inwardly extending substantially juxta-positioned lips serving partly to form a bearing recess, the said reservoir having an opening between said lips for the passage of lubricant to the bearing.
11. In a pulley block, a rotatable sheave, a shaft carrying and rotatable with said sheave, side plates having bearings for said shaft, and a pair of independent separated lubricant reservoirs in each side plate dis-

posed on opposite sides of the bearing, each plate having openings whereby the reservoirs communicate with the bearing.

12. In a pulley block, a rotatable sheave, a shaft carrying and rotatable with said sheave, side plates having bearings for said shaft, a pair of independent separated lubricant reservoirs in each side plate disposed on opposite sides of the bearing, each plate having openings whereby the reservoirs communicate with the bearing, and means for independently filling each reservoir.

In testimony whereof, I have hereunto set my hand.

FREDERICK B. MALLORY.
